UNITED STATES PATENT OFFICE.

JULIUS PEGEL, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 14,273, dated September 11, 1883.

Application filed July 28, 1883. Term of patent 3½ years.

To all whom it may concern:

Be it known that I, JULIUS PEGEL, of New York city, New York, have invented a new and original Design for Carpets, of which the following is a specification, reference being had to the accompanying photograph, which forms a part of the same.

The invention relates to a design to be worked into or upon surfaces—such as carpets or similar fabrics; and it consists in the novel configuration and grouping of figures herein specifically shown and claimed.

The accompanying photograph is a face view of a carpet showing my new design.

The design consists of several large flower groups disposed over an ornamented ground, which ground, however, is not continuous over the whole face of the design in the photograph, although it may be made so. The photograph clearly shows the design in its details.

I claim—

The design for a carpet, substantially as shown and described.

JULIUS PEGEL.
